United States Patent Office.

JAMES S. UPTON, OF BATTLE CREEK, MICHIGAN.

Letters Patent No. 82,455, dated September 22, 1868.

IMPROVEMENT IN SHAFT-COUPING.

The Schedule referred to in these Letters Patent and making part of the same.

TO ALL WHOM IT MAY CONCERN:

Be it known that I, JAMES S. UPTON, of the city of Battle Creek, in the county of Calhoun, and in the State of Michigan, have invented a Safety Coupling-Ring for Threshing-Machines; and do hereby declare that the following is a full, clear, and exact description thereof, reference being had to the accompanying drawings, and to the letters of reference marked thereon.

The nature of my invention consists in providing the ring of a safety-coupling with slots in which leather or other keys are inserted to keep the pins from moving out, thereby preventing any accidents which are liable to occur when the pins protrude on the outside of the ring, by catching in persons' clothes and dragging them on to the shaft.

In order to enable others skilled in the art to make and use my invention, I will now proceed to describe its construction and operation, referring to the annexed drawings, which form a part of this specification, and in which—

Figure 1 is a front view, and

Figure 2 a sectional side view.

A represents the coupling-ring; B B, the sockets in which the shaft is inserted. These sockets are, on their inner end, provided with gudgeons C C, which are inserted into the ring A. Pins $\alpha\alpha$ are put through the ring A, and through the gudgeons C C, at right angles to each other, as shown in fig. 1.

At the ends of each of these pins, slots $\alpha\alpha$ are made through the said ring, and in these slots leather or other keys are inserted, which effectually prevent the pins from moving outward in either direction.

Having thus fully described my invention, what I claim as new, and desire to secure by Letters Patent, is—

The sockets B B, provided with gudgeons C C, and connected to the slotted ring A by means of the pins $\alpha\alpha$, secured in the slots $\alpha\alpha$ by the leather keys, all as herein shown and described.

In testimony that I claim the foregoing, I have hereunto set my hand, this 10th day of July, 1868.

JAMES S. UPTON.
